UNITED STATES PATENT OFFICE.

PAUL BABCOCK, JR., OF MONTCLAIR, NEW JERSEY.

MEANS FOR CLOSING CANS.

SPECIFICATION forming part of Letters Patent No. 321,568, dated July 7, 1885.

Application filed May 7, 1885. (No model.)

To all whom it may concern:

Be it known that I, PAUL BABCOCK, Jr., of Montclair, in the county of Essex and State of New Jersey, have invented a new and useful Improvement in Means for Closing Cans, 5 of which the following is a specification.

My invention is intended more particularly for sheet-metal cans, such as are employed in shipping oil or kerosene; but the invention is 10 also applicable to cans for containing other liquids. In cans for oil it has been customary to form in the head of the can a large pouring or filling hole, and, after the can is filled, to solder over and around this hole a circular 15 top, closing piece, or cover, of zinc, thin sheet-tin, or other metal, having upon it a circular projection, to which a cap is applied. This cap is ordinarily screw-threaded to fit a screw-thread spun or formed in the closing piece or 20 cover, and when the can is shipped this closing piece or cover is entirely imperforate and hermetically seals the can, the cap being screwed on or applied to its exterior. When 25 the can is to be opened and its contents used, a circular hole is cut in the closing piece or cover, which may be readily done by a knife, because of the soft or thin metal of which the cover is made, and thereafter the can may be closed by the screw-cap which is applied to it; 30 hence it will be seen that ordinarily when a can is closed and shipped it is hermetically sealed by one very thin thickness of sheet metal, and if this becomes punctured or fractured either by reason of the metal cracking 35 when the screw-thread is spun or formed upon it or by reason of its rusting away, or from any other cause, there will be a leakage, as the oil swashes back and forth in the can during a voyage or in the handling.

40 The object of my invention is to provide a means for closing cans which shall afford the same facility for opening them by readily cutting the metal with a knife, and which shall afford greater security against any leakage.

45 To this end the invention consists in the combination, with a can having a pouring or filling hole in its head, of a closing piece or cover soldered to the head around the pouring or filling hole, and having a circular projection, on which a cap is secured, and the top 50 of which is imperforate, and also having a base portion which is imperforate, both the

top of the circular projection and the base portion being of thin metal, so that they may be readily cut with a knife, and forming between them an intervening space. When the can is thus closed, there can no leakage occur, even if the top of the closing-piece or its circular projection be fractured by spinning the thread thereon or otherwise, because the base 55 portion of the closing-piece which is imperforate will prevent any leakage.

In the accompanying drawings, Figure 1 represents a sectional view of a portion of a can having my invention applied thereto. 60 Fig. 2 is a sectional view of a closing-piece having a screw-threaded circular projection and an imperforate base portion combined together and ready to be secured to a can-head. Fig. 3 represents the closing-piece before its 65 imperforate base portion is applied to it. Fig. 4 represents a sectional view of the base portion of the closing-piece alone, and Fig. 5 represents a sectional view similar to Fig. 2, and showing a closing-piece which has a plain circular projection without a screw-thread and a plain cap with a straight rim applied thereto. 70

Similar letters of reference designate corresponding parts in all the figures.

A designates a portion of the head of a can, 80 which may be made of tin or other sheet metal, and in which is a large filling-hole, a. In the head of the can around the filling-hole is a circular indentation, a', whereon is secured a closing piece or cover, B.

In making the closing-piece or cover B, I first take a circular piece of sheet metal and strike it up into the form shown in Fig. 3, with a downwardly and outwardly flaring flange, b, and a circular upward projection, b'. 85 The top b' of this closing-piece will be imperforate, and I may form therein an annular groove, *, which constitutes a guide for cutting out the top by means of a knife when it is desired to open the can. The closing piece 90 also comprises a base portion, B', which consists of a circular piece of metal slightly longer in diameter than the piece B, and struck up to give it the form shown in Fig. 4, it having an outwardly and downwardly flaring flange, b'. 95 In the top of this base portion B', I also may form a circular groove or indentation, *, which forms a guide for the knife in cutting out the base portion when it is desired to open 100

the can. The circular projection b' may have formed in it a portion of a screw-thread, which may be done by spinning, and which is shown in Figs. 1, 2, and 3, and to such projection is applied 5 a screw-threaded cap, C, which is shown in Fig. 1, and which is composed of thicker metal. The pieces B B', which constitute the closing-piece for the can, should be made of "taggers tin" or other thin metal, which may be 10 readily cut by a knife or other sharp-edged tool.

In lieu of making the circular projection b' with a screw-thread it may have a plain cylindric exterior, as shown in Fig. 5, and in 15 such case the cap C would have a straight cylindric rim.

The two pieces B B' which constitute the closing-pieces are preferably combined together, as shown in Figs. 1, 2, and 5, the outer 20 edge of the portion B' being folded over and inward upon the outer edge of the portion B. After the can is filled, the closing-piece B B' is placed in the indentation a' , around the filling-hole a , and is tightly secured to the can-head

25 A by solder. The cap C is screwed upon or slipped over the circular portion of the closing-piece B B'. It will therefore be seen that in the closing-piece B B' are two portions of thin metal, which must be cut in order to open the

can, and which form between them an intervening space, B*. If the portion B of the closing-piece be fractured or perforated in any way by reason of the metal breaking while forming the screw-thread upon it, or from any other cause, there will be no opening into the can, 35 because the can will be hermetically closed by the imperforate base portion B' of the closing-piece; or, in like manner, if the base portion B' be accidentally perforated the top b^2 of the portion B will remain imperforate and will 40 maintain the can hermetically sealed.

What I claim as my invention, and desire to secure by Letters Patent, is—

The combination, with a can-head having in it a filling-hole, of a closing-piece comprising a portion, B, formed with a circular projection, upon which is fitted a cap and a base portion, B', the top of the circular projection and the base portion being of thin metal, so that they may be readily cut away, and forming between them an intervening space, substantially as and for the purpose herein described. 45 50

PAUL BABCOCK, JR.
